J. F. FLOOD,
WILLIAM JOHNSON.

UNITED STATES PATENT OFFICE.

GEORGE E. SHARPE, OF STEUBENVILLE, OHIO.

DESIGN FOR A FIRE-PLACE FRONT.

SPECIFICATION forming part of Design No. 15,699, dated January 6, 1885.

Application filed October 28, 1884. Term of patent 7 years.

To all whom it may concern:

Be it known that I, GEORGE E. SHARPE, a citizen of the United States, residing at Steubenville, in the county of Jefferson and State of Ohio, have invented certain new and useful Improvements in Designs for Fire-Place Fronts and Fenders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The accompanying photographs fully illustrate my new design.

The letter A designates a frame having an arch-shaped opening surrounded by the double convex molding B, the inner edge of which is finished with a narrow bead, C.

D is a fender composed in the main of the concave moldings d d, and having the outwardly-inclined feet e e.

F is a top rail supported by short posts f f. The combination and peculiar arrangement of the moldings give the fender an appearance of solidity and gracefulness at the same time and form a pleasing contrast with the convex molding surrounding the fire-place opening.

G is an open-work summer piece composed of the open-work border g and the inner open-work panel surrounded by the molding h, said panel representing an ornamental open-work trellis, H, up the sides of which climb the vines I from the vases k k.

What I claim is—

1. The design for a fire-place front, consisting of the frame with arched opening surrounded by the broad convex molding, and 40 the fender composed in its outer configuration, mainly, of concave moldings and spreading from top to bottom, while on its top are short posts upon which rests a rail which widens gradually from top to bottom, as 45 shown.

2. In a design for a fire-place front, the frame with the arched opening, the summer piece filling said opening, and having an ornamental open-work border surrounding an open-work panel representing a trellis with vines climbing up the sides thereof, substantially as shown.

3. In a design for a fire-place front, the frame with the arched opening, the summer 55 piece filling said opening and having the open-work border surrounding an inner panel representing a trellis with vines climbing thereon, and the fender at the foot of the frame and representing the frustum of a pyramid built 60 up mainly of concave moldings and surrounded by a rail which grows gradually wider from top to bottom and is represented as resting upon short posts, as set forth.

In testimony whereof I affix my signature in 65 presence of two witnesses.

GEORGE E. SHARPE.

Witnesses:

J. F. FLOOD,
WILLIAM JOHNSON.
